UPHOLSTERY

Harold E. Williams, Carthage, Mo.

Application June 17, 1935, Serial No. 26,935

1 Claim. (CL 5—354)

My invention relates to improvements in upholstery. It relates particularly to spring covering pads adapted for use on metal spring structures, such as are employed in inner spring mattresses, spring seats, spring beds, upholstered furniture and the like.

One of the objects of my invention is to provide a novel spring covering pad of the kind described which is particularly well adapted for use on the top of coil spring structures, which is provided with novel means for preventing the spring covering pad from getting down into or between the coil supporting springs, and which is an integral structure adapted for insertion into or removal from an upholstered spring construction as a unit.

A further object of my invention is the provision of a novel spring covering pad of the kind described, which is simple, cheap, strong and efficient.

The novel features of my invention are hereinafter fully described and claimed.

In the accompanying drawing which illustrates my invention,

Fig. 1 is a plan view, partly broken away, of my improved spring covering pad.

Fig. 2 is a plan view, partly broken away, of a portion of one form of my improved sinuously formed spring strip member for supporting the padding sheet.

Fig. 3 is a section, enlarged, on the line 3—3 of Fig. 2.

Fig. 4 is a vertical sectional view, enlarged, of my improved spring covering pad shown mounted on coil springs and embodying the sinuous spring strip with the binding strips shown in Figs. 2 and 3.

Fig. 5 is a plan view of the sinuously formed spring strip shown attached by stitching to a portion of a sheet of fabric.

Fig. 6 is a reduced plan view of a modified means for spacing the folds of the sinuous member.

Fig. 7 is an enlarged section on the line 7—7 of Fig. 6.

Fig. 8 is a reduced diagrammatic view showing the fabric sheet, the sheet of padding, and the sinuously formed sheetlike spring layer being fed into a pile one superposed above the other preparatory to the three layers being stitched together.

Similar characters of reference designate similar parts in the different views.

1 designates an ordinary sheet of felted cotton padding, 2 a fabric sheet, such as burlap or

canvas, which is usually mounted on to tops of coil springs 3 of a bed bottom, seat, inner spring mattress or the like.

To prevent the fabric sheet 2 and the padding sheet 1 being forced downwardly into or between the coils 3, my invention provides a sheetlike layer, preferably disposed between the sheets 1 and 2, and comprising a sinuously formed spring strip 4, preferably spring wire. The sinuously formed wire 4 is formed into a flat layer of slightly less width than the width of the sheets 1 and 2, and its folds are held spaced apart, in the form shown in Figs. 1, 2, 3 and 4, by pairs of flexible gummed strips 5, disposed respectively adjacent opposite edges of the layer. The gummed strips 5, which may be of paper or other suitable material, are disposed at opposite sides of the wire layer 4, and are made to adhere to each other and to the sinuous wire between the folds of the latter.

Such binding together of the folds of the sheetlike wire layer, holds the folds from expanding apart, and enables the layer to be formed into a roll, as designated by 4, Fig. 8, from which it may be fed forwardly between padding sheet 1 and the burlap sheet 2, which sheets may also be fed rolls to superposed positions respectively above and below the sheetlike layer 4, at which positions the three layers may be simultaneously stitched together, as designated by 6, in Figs. 1 and 4.

The stitching 6 is preferably extended transversely across and between the folds of the wire layer 4, as shown in Fig. 4, thereby firmly holding the wire layer 4 from shifting between the sheets of padding and fabric.

By disposing the wire layer 4 above the fabric sheet 2, the wire layer is kept from contact with the upper ends of the coil springs 3 upon which rests the fabric sheet 2, thus eliminating scratching noises which might be made were the wire layer 4 in contact with the coils 3.

By providing the long sheets of padding, fabric and wire layer, disposing them in rolls, and then feeding them from the rolls, and simultaneously with the feeding operation, stitching the superposed layers simultaneously together, a very economical and simple method of manufacture of the spring covering pad is effected, which enables a large output in a relatively short time. By having the rows of stitching 6 extending lengthwise of the three layers and transversely across the wire sections and between the folds of the sinuously formed strip 4 at intervals between the folds, the folds are held throughout from spread-

ing apart, and the stitching operation can be effected continuously simultaneously with continuous forward feeding of the three layers, thus effecting a saving of time and an increased efficiency in the product.

As the assembled stitched together layers are produced, they may be transversely severed to lengths suited for the particular purpose for which they are to be used.

10 In Fig. 6 and Fig. 7 is shown a modified form of binding the folds of the sinuously formed wire to each other. In this form, two longitudinal strips of cloth, as canvas, 7, are folded lengthwise and are made to respectively embrace the bends 15 of the folds of the wire 4 at opposite edges of the wire layer. Opposite portions of each strip 7 are then sewed together between the folds 4.

The strips 7, thus hold the folds from expanding away from each other. In case it is desired 20 to hold the folds of the sinuous strip 4 from contracting toward each other, as well as from expansion from each other, the strips 5 may be resilient material, as spring steel or brass, and opposing strips of each pair may be fastened 25 to each other by welding, soldering, riveting or otherwise.

As shown in Fig. 5, the sinuous strip 4 may be fastened alone to the fabric sheet 2 by stitching 30 8 extending transversely across and between the folds of the strip adjacent to the bends thereof.

The spring strip 4 having been sinuously formed and the folds thereof bound together, in the manner described, to form a sheetlike layer, said layer may be formed into a roll, as 35 shown in Fig. 8, for convenience in handling and storing. The wire therefrom may then be fed from the roll and interposed between padding and fabric respectively simultaneously fed from rolls 1 and 2, and, while being so fed, the three

layers may be simultaneously stitched together, as has been described, and as is shown in Figs. 1 and 4. The combined layers may then be transversely severed into sections of desired dimensions and of substantially even thickness 5 throughout.

Such sections may then be disposed in suitable casings, not shown.

The sinuous strip layer will hold the padding 1 from shifting and from entering between or into 10 the springs 3. My improved spring covering pad, constructed as hereinbefore described, constitutes an integral structure, adapted for individual storage, shipment and for insertion into or removal from an upholstered spring construction of usual type as a unit, whereby manufacturers of such spring constructions may obtain 15 the unit and insert it therein, without requiring it to be built up piece by piece therein, thus affording economy in the manufacture. 20

Other modifications of my invention, within the scope of the appended claim, may be made without departing from its spirit.

What I claim is:—

In a spring covering pad, three layers, 25 each layer having substantially even thickness throughout, comprising a fabric sheet, a sheet of padding, and a sheetlike spring strip formed of sinuously bent wire between said sheets, and rows of stitching extending through the three 30 layers transversely across and between the folds of said spring strip at intervals between the folds, whereby the folds are held from spreading apart throughout their lengths and the three layers are united together to form an integral structure 35 of even thickness throughout and adapted for insertion or replacement as a unit.

HAROLD E. WILLIAMS.
